WALL RACK

Olley C. Lauber, Archbold, Ohio

Application November 29, 1954, Serial No. 33,296

Term of patent 14 years

(Cl. D33—3)

FIG. 1.

FIG. 2.

To all whom it may concern:

Be it known that I, Olley C. Lauber, a citizen of the United States and a resident of Archbold, in the county of Fulton and State of Ohio, have invented a new, original, and ornamental design for a Wall Rack, of which the following is a specification, reference being had to the accompanying drawing, forming a part thereof.

In the drawing,

Fig. 1 is a perspective view of a wall rack embodying my new design, and

Figs. 2 and 3 are end and top views thereof, respectively.

I claim:

The ornamental design for a wall rack, substantially as shown.
